UNITED STATES PATENT OFFICE

CHARLES W. MORDEN, OF PORTLAND, OREGON, ASSIGNEE TO MORDEN MACHINES COMPANY, OF PORTLAND, OREGON, A CORPORATION OF OREGON

PULP TREATING MACHINE

Application filed April 1, 1930. Serial No. 440,732.

In the manufacture of paper stock from pulp, two machines are ordinarily used, one the "beater" and the other the "Jordan", both being machines well known to those familiar with the art of paper manufacture.

In the beater, the pulp is treated in large batches, each batch being recirculated in the beater tub, during its treatment, by the rotation of the beater roll and caused to pass once each circulation between the beater roll and a stationary bed plate which acts to rub out, separate and promote the hydration of the pulp fibres.

The beater does not circulate the pulp uniformly during its treatment and the machine itself is large and occupies considerable floor space. Further, since the pulp is only acted upon once during each circulation by the beater roll and bed plate, a large number of circulations of the mass of pulp is required for each portion of it to receive the requisite treatment. This greatly prolongs the beating period and requires an excess of power which is practically wasted in circulating the mass of pulp around the tub.

In the Jordan, which also occupies a relatively large floor space, since its plane of operation is horizontal, the pulp is passed continuously through the machine and is thereby given a supplementary treatment just before going to the paper machine and after having been treated in the beater, whereby the way in which the pulp will form into a sheet of paper on the paper machine is in part controlled.

Since the operation of the Jordan is continuous, the only control of the pulp is by the adjustment of the attritioning elements to operate more or less severely on the pulp as it passes through the machine.

In the preparation of the pulp, prior to its treatment in the beater and Jordan, as above described, the pulp is screened and the rejected portions are subjected to further treatment in machines called refiners, the primary function of which is to reduce the size of the pulp particles sufficiently to pass through the screens. In such refining operations, it is customary to thicken the pulp in machines known as thickeners before it goes

to the refiners, and after the pulp leaves the refiners it is necessary that it be again screened.

The object of my invention is to provide an improved pulp treating machine so constructed as to occupy but relatively little floor space and adapted to function either as a beater or Jordan, or as a combined beater and Jordan. Such machine having the advantages of both beater and Jordan in that the desirable recirculation of pulp of the beater is combined with the efficient attritioning action of the Jordan, and at the same time the undesirable features of these machines are eliminated in that a controlled recirculation under pressure is provided whereby the pulp is more efficiently treated and hydrated without consuming an excess of power ordinarily wasted in the recirculation of the pulp.

A further object of my invention is to provide a pulp treating machine adapted to recirculate the pulp within itself in relatively small batches, which are automatically delivered to the machine and discharged therefrom by the automatic introduction of the next batch of pulp, thus providing a substantially uninterrupted and continuous batch operation.

I attain my objects in a pulp treating machine comprising an attritioning element consisting of, two cooperating members relatively rotatable, an annular passageway encompassing the said attritioning element and connecting the intake and discharge ends of the same, the walls of said annular passageway being relatively arranged to induce substantially uniform travel of all particles composing the material passing through said passageway and having chambers communicating with said annular passageway at the intake and discharge ends of the attritioning element, said chambers being provided, respectively, with the inlet and the outlet for the material and automatic means for feeding and discharging successive batches of material to and from the machine, such means adapted to hold the batch in the machine for a predetermined interval and to discharge the same by displacement due to

the feeding of a further batch of material to the machine.

A further object of my invention is to provide such a machine which is adapted by a slight change, to continuously refine pulp screenings as rejected by pulp screens, said machine being adapted to thicken the screenings prior to the refining treatment and to screen the same after the refining treatment.

10 A further incidental object of my invention is to provide a machine adapted for operating upon wood chips or other fibre bearing material, to produce pulp suitable for the manufacture of wall board and the like, by merely substituting for one type of attritioning element provided in the machine another type, thereby to adapt the attritioning elements to handle relatively large units of raw material.

15 20 These and other incidental objects of my invention, the details of construction and mode of operation thereof are hereinafter fully described with reference to the accompanying drawings:

25 In the drawings:

Fig. 1 shows a central, vertical section taken through my pulp treating machine and illustrates how the pulp is recirculated and the automatic batch delivery means;

30 Fig. 2 shows a side elevation of my machine provided with electrically controlled batch delivery means;

35 Fig. 3 shows in a vertical section another form of my machine and illustrates the recirculation of the pulp therein and the particular form of attritioning elements provided;

Fig. 4 shows a side elevation of my machine as illustrated in Fig. 3;

40 Fig. 5 shows a section taken on the line 5—5 of Fig. 4 and illustrates the relative arrangement of the annular inlet passageway;

45 Fig. 6 shows a section taken on the line 6—6 of Fig. 3, and illustrates the relative arrangement of the impeller blades and screen; and

50 Fig. 7 shows a section taken on the line 7—7 of Fig. 3 and illustrates further details of the particular form of attritioning elements provided.

Referring now to Fig. 1: I have shown my improved pulp treating machine adapted to function on the pulp in batches either as a beater or Jordan, or as a combined beater and Jordan, the use to which it is put depending entirely upon the class of pulp to be operated upon and the results desired. The latter to be obtained by the adjustment of 60 the attritioning element and the length of the period of treatment.

The machine comprises a base *a* supporting an upright cylindrical housing *b* having on its top a vertically arranged motor *c*. The 65 housing *b* is provided with an inlet *d* con-

nected with a source of pulp which will be again referred to.

Within the housing *b* below the inlet *d* is provided a vertically movable annular shell *b'*, having downwardly converging sides and provided with a longitudinal annular passageway *h* within its walls. The exterior of the shell *b'* adjacent the housing *b* is provided with adjustable packing gland *j* to form a fluid tight seal therewith. An outlet *e* is provided in the lower part of the shell *b'* to which is connected an upwardly extending conduit *f*, discharging into a larger open conduit *g*. By these means a head of pressure is maintained within the machine.

To control such head of pressure, I provide a relief valve *p* preferably of the ball type at the upper end of the conduit *f* and an outwardly opening check valve *o* provided with a counter weight *o'* in the outlet *e* to prevent the circulation of pulp into and out of the said outlet, as hereinafter further described.

2 A shaft 2 is connected to the lower end of the motor shaft *c'*. The upper end of the said motor shaft *c'* is journaled in a thrust bearing 3 so that the weight of the shaft 2 is entirely supported thereby. The shaft 2 is journaled at its lower end in the bottom of the shell *b'* in suitable bearings *k* preferably of the "cutless rubber, water lubricated type".

3 A frusto-conical plug or rotor 4 is provided on the shaft 2, located within the frusto-conical chamber formed by the shell *b'*, the opposed surfaces of said plug and shell being provided with suitable bar or abrasive attritioning surfaces 1 familiar to those skilled in the art. The larger end of said rotor 4 is located adjacent the inlet *d* of the machine.

4 These means constitute the attritioning elements of my machine and are relatively adjustable to and from each other by means of a worm and gear *m* carried by the base *a* on bearings *m2* and meshing with threads *m'* provided in the exterior of the lower part of the shell *b'*, whereby the shell *b'* may be moved to or from the said plug or rotor 4.

5 Radial impeller blades 10 are bolted to the top of the plug or rotor 4 and the inlet *d* is connected therewith through a passageway 11, formed within the housing *b*.

6 The radial impeller blades serve to throw the pulp entering through the passageway 11 in an annular ring into the passageway *h*, and also tend to serve as a seal and as means for maintaining pressure within the machine during the treatment of the pulp.

7 The inlet *d* is connected with the bottom of an open vat 20, into which pulp is supplied from a pipe 21, leading from the source of supply and arranged to discharge onto a self-emptying hopper 22, which is pivotally mounted on a horizontal shaft 23, and comprises two similar bins 24, 25 located on each side its pivotal axis.

An upright arm 26 is provided on the said hopper having an adjustable counter weight 26a on the end. Spaced stops 27 are provided on the upper rim of the vat which limit the possible arcuate movement of the arm 26 and hence that of the hopper 22 in such a manner that as one bin becomes filled, it will cause the hopper to tip and discharge the filled bin, by its weight, into the vat at the same time bringing the bin 24 under the pipe 21, which will then be filled and similarly emptied.

By this construction, the pulp may be automatically fed into my machine in batches, the interval at which each batch is supplied being controlled by the rate of flow from the pipe 21, for this purpose a valve 21a is provided.

In the operation of my machine, as above described, with reference to Fig. 1, the pulp flowing from the pipe 21 fills the bin 25 of the hopper 22, until it overcomes the counter weight 26a and tips, emptying the pulp into the vat 20.

Then, assuming this to be the first batch of pulp introduced into the machine, the pulp flowing into the inlet *d* from the vat will be picked up by the revolving impeller blades 10, and be thrown against the walls of the housing *b* and pass downward through the annular passageway *h* into a chamber *b2* formed in the bottom of the shell *b'*.

At this time the check valve *o* will remain closed, since the pressure of the pulp will be insufficient to open it, and the pulp will be drawn upward between the attritioning elements by the centrifugal force of the rotating plug 4, which creates a pumping action and the pulp is there acted upon continuously and at all points on the peripheries of the shell and plug until it is discharged at the top of the plug and again passes downward through the passageway *h*. Thus the pulp may be recirculated and passed between the attritioning elements 1 as many times as desirable to produce a given grade of pulp.

Therefore, in my machine the pulp will be acted upon by the attritioning elements during approximately half of each circulation, and practically no excess power will be required for the mere recirculation of the pulp since it will tend to flow by gravity through the passageway *h* for the completion of each circulation.

Further since the pulp will be attritioned and recirculated under pressure through the passageway *h*, which is arranged to induce substantially uniform travel of the pulp particles, the uniform hydration of the same will be promoted and the degree of attritioning desired may be attained by the adjustment of the shell *b'* relatively to the plug 4 to provide more or less severe attritioning action.

I will now describe the further operation

of my machine in which each successive batch of pulp is automatically displaced as follows:

When the bin 24 of the hopper 22 has filled and emptied the new batch of pulp entering the inlet *d* and acted upon by impeller 10, is delivered in an annular mass into the passageway *h* and displaces the pulp therein and forces it into the chamber *b2* where the increase of pressure will open the check valve *o* and relief valve *p*, and the displaced pulp will be forced by the pressure of the new batch of pulp out of the machine and into the conduit *g*.

Thus it is apparent that my machine combines the desirable recirculation of the pulp, as in the beater, and the efficient attritioning action of the Jordan and at the same time provides a controlled recirculation under pressure accomplished without consuming excess of power in recirculating the pulp.

However, this form of my machine may be adapted for continuous operation by merely reversing the direction of flow of the material into and out of the machine, in which case the relief valve *p*, the check valve *o*, and the batch feeding means will of course be removed, so that the material entering the machine at *e* will be drawn up between the plug 4 and the shell *b'* by the pumping action of the rotating plug, and depending on the relative rate of introduction of the material at *e* to the pumping action of the plug, a greater or less amount will be recirculated through the passageway *h* and there will be a steady delivery of pulp out of the machine at 11.

Further, it may be desirable for some classes of work to utilize my machine as a straight Jordan, in which case the annular passageway *h* will be closed by a suitable closure plate at its lower end, so that the material will then pass between the plug and shell and directly out of the machine at 11.

In Fig. 2, I show another means for automatically feeding batches of pulp into my machine at predetermined intervals, which provides a somewhat more positive action.

My machine is illustrated diagrammatically at 30. Its inlet 31 is connected through a pipe 32 with an open vat 33 provided with transverse partitions 33a, 33b, the partition 33a is provided with an opening at the bottom controlled by a gate 34 and the partition 33b does not extend upwardly to the rim of the vat. The space between the partitions 33a, 33b is connected at the bottom with a source of pulp as at 35, and the space between the partition 33b and the end of the vat is provided with an outlet 36 connected with the source of pulp. By this construction pulp under constant head is provided at the gate 34 since pulp entering from the

inlet 35 will overflow the partition 33b and out through the outlet 36 continuously.

A float 38 is provided in the vat operatively connected as at 38a with a two way switch 39, which controls electric circuits 40, 41, leading to a reversible motor 42 and connected to a source of power 43.

The motor 42 is connected through a worm and pinion gear 42a with a valve 44 in the outlet 45 of my machine. The valve stem 44a is also operatively connected as at 44b with a two way switch 46 also in the said circuits 40, 41.

By these means, when the pulp in the vat 15 reaches the level shown in the figure, the switch 39 will assume the position there shown, which will close the circuit 40, the switch 46 at this time also being positioned to close the said circuit 40 and actuate the 20 motor 42 to open the valve 44 and permit the batch of pulp herein to discharge, as before described with reference to Fig. 1. When the valve 44 is fully opened the switch 46 will break the circuit 40 and stop the motor at the same time closing the circuit 41 so that when the vat has emptied, the float 38 will fall to its lowermost position and cause the switch 39 to also close the circuit 41 and actuate the motor 42 in the reverse direction 25 to close the valve 44.

Referring now to Figs. 3 to 7, inclusive: I show a complete form of my pulp treating machine, adapted either for the refining of the pulp rejected from pulp screen or for 35 batch operation in the treating of pulp as previously described. This form is similar in its essential features to the machines before described and comprises:

A base 50 supporting a housing 51, which 40 in turn supports a motor 52. The motor shaft 52a is supported at the top by a thrust bearing 53 and has a shaft 54 connected to its lower end on which a rotor 55 is mounted carrying attritioning means, hereinafter further described. The lower end of the shaft 45 54 is journaled as at 55a in a longitudinally movable shell 56 mounted within the housing which is adjustable relatively to the rotor 55 by a worm and gear 57, as before described 50 with reference to Fig. 1.

A longitudinal annular passageway 59 is provided within the wall of the said shell 56 terminating in the bottom in chamber 59a. The inner face of the shell, adjacent the rotor 55 is provided with a suitable attritioning 55 lining 56a.

An inlet 60 is provided in the housing 51 leading through a passageway 60a into the center of an annular chamber 61 located 60 above the rotor 55 and the shell 56, having provided therein a spaced concentric, cylindrical, perforated plate or screen 62, and an outlet 61a leading from the periphery of the said chamber.

Within the screen 62 are provided primary

and secondary radial impeller blades 63, 64 carried by the said shaft 54. The blades 63, 64 are integral, but perform different functions, the blades 63 are of greater length and positioned just below the discharge end of the passageway 60a; and the blades 64 extending below are inclosed by an integral, cylindrical wall 65. The exterior of the wall 65 is provided with supplementary radial blades 66 in the same cylindrical plane as the primary blades 63, but relatively arranged so as to lie between the vertical planes of the said primary blades.

The shell 56 is provided with a stationary, upwardly converging wall portion 67, secured thereon on the upper rim of the inner wall of the annular passageway 59 and forms in part with the impeller wall 65, in which the wall portion 67 is slidably journaled annular passageways 68, 69 on each side. The passageways 68, 69, respectively, lead to the passageway 59 in the shell 56 and from above the rotor 55 to the said secondary blades 64.

In operation this form of my machine performs the function of thickening the rejected pulp as it comes from the screens to a suitable consistency for being further refined, of refining the pulp and finally screening it again, and thus takes the place of the several machines now required for this purpose.

The operation is as follows: Pulp flowing continuously into the inlet 60 is received on the primary impeller blades 63 and the supplementary blades 66 and is thrown against the screen 62. The pulp, being too large to pass through the screen 62, is held in the machine, but a portion of the water however does pass through the screen 62 and out through the outlet 61a, and thus the pulp is thickened. The thickened pulp then passes downward through the passageway 68 into the annular passageway 59 around the shell and into the chamber 59a from where it is drawn upward by the centrifugal action of the rotor 55 and the pumping action of the secondary impeller blades 64 between the rotor 55 and the lining of the shell; and is there acted upon to reduce its size and to be otherwise refined. The pulp is then discharged from between the rotor 55 and the shell at the top and passes through the passageway 69 to the secondary and primary impeller blades and is there mixed with and diluted by the incoming dilute pulp and is then again thrown against the screen 62 and the portion which has been sufficiently reduced in size will pass therethrough, with the water separated from the incoming pulp and the rejected portion will again be circulated and acted upon by the attritioning elements until it is sufficiently refined and reduced in size to pass the screen.

Further, in this modification of my machine, the attritioning means carried by the

rotor 55 are adapted for operating upon wood chips or other fiber bearing material to produce pulp suitable for the manufacture of wall board and the like. These attritioning means are of the "swing hammer" type and comprise a series of parallel spaced circular plates 80 fast on the shaft 54 of graduated diameters in order to conform with the shape of the frusto-conical chamber formed by the shell 56. Between the plates 80 are pivotally mounted on rods 81, a series of elongate hammers 82 also of graduated lengths to conform with the shape of the frusto-conical chamber. The said hammers 82 are of such length as to extend beyond the peripheries of the plates 80, and when in radial alinement with the shaft 54 to almost touch the lining of the shell 56, depending on the relative longitudinal, adjustment of the said shell.

By this construction, as the relatively coarse pieces of wood or the like are drawn upward from the chamber 59a, the hammers may yield, but due to the centrifugal force of their rotation will tend to remain in radial alinement and thus with the shell lining will act upon the chips to break down their physical structure and reduce them to pulp, usable for the manufacture of wall board and the like.

For this work a relatively coarser screen will be provided than the screen 62 provided for the refining of screenings.

Further, this machine, either with the attritioning means 80, 82 here described, or the plug 4, may be adapted for the refining of pulp as described with reference to Fig. 1, by substituting a solid plate for the screen 62 and opening the outlet 85 in the chamber 59a. It would then be preferable to supply the pulp in batches by such means as are illustrated in Figs. 1 and 2.

Whereas the machine and method herein described have been described as relating to the treating of pulp, it is obvious that they are applicable to other materials than pulp such as materials now treated in colloid mills for example.

I claim:

1. In a machine of the character described, an attritioning element comprising, a conical shell and a rotor relatively adjustable, the rotor provided with a series of radial pivoted hammers of graduated length adapted to operate with the conical shell to attrition the material passing therethrough, an annular passageway encompassing the shell and connecting the intake and discharge ends of said attritioning element, an inlet and outlet for the material communicating with said annular passageway and automatic means for feeding and discharging successive batches of material to and from the machine, such means adapted to hold the batch in the machine for a predetermined interval and to dis-

charge the same by displacement due to the feeding of a further batch of material to the machine.

2. A pulp treating machine comprising, an upright housing, a vertically arranged motor supported on said housing, an attritioning element consisting of a conical shell vertically adjustable in said housing, a rotor carried by the motor shaft and located within the shell, and cooperating attritioning means carried by the rotor and the shell, respectively, an annular passageway encompassing the shell and connecting the intake and discharge ends of said attritioning element, a chamber provided with an inlet port for the pulp, having perforated walls constituting a screen element, the chamber communicating respectively with said annular passageway and the discharge end of said attritioning element, the exterior of said chamber communicating with an outlet port for the pulp and an impeller element in said chamber comprising primary and secondary blades, the primary blades located adjacent the inlet port and the secondary blades adjacent the discharge end of the attritioning element.

3. A pulp treating machine comprising, an upright housing, a vertically arranged motor supported on said housing, an attritioning element consisting of a conical shell vertically adjustable in said housing, a rotor carried by the motor shaft and located within the shell, and cooperating attritioning means carried by the rotor and the shell, respectively, the attritioning means of the rotor consisting of a series of radial pivoted hammers of graduated lengths relatively to the cross sectional area of the shell, adapted to cooperate with the attritioning means of the conical shell, an annular passageway encompassing the shell and connecting the intake and discharge ends of said attritioning element, a chamber provided with an inlet port for the pulp, having perforated walls constituting a screen element, the chamber communicating respectively with said annular passageway and the discharge end of said attritioning element, the exterior of said chamber communicating with an outlet port for the pulp, and an impeller element in said chamber comprising primary and secondary blades, the primary blades located adjacent the inlet port and the secondary blades adjacent the discharge end of the attritioning element.

4. In a machine of the character described, an attritioning element comprising two relatively rotatable members, said attritioning element having peripherally disposed inlet and outlet, a peripherally disposed passageway encompassing said attritioning element connecting the said inlet and outlet thereof, means causing the repeated circulation of material within the machine, said machine provided with a screen element in said pas-

sageway adapted to retain in the machine that portion of the material not sufficiently treated and permit the rest of the material to escape.

5. In a machine of the character described, an attritioning element comprising a shell and a rotor, said attritioning element having a peripherally disposed inlet and outlet, a peripherally disposed passageway encompassing said attritioning element and connecting the said inlet and outlet thereof, the cross section of said passageway and the arrangement thereof relatively to said inlet and outlet being adapted to cause all particles of material passing from the outlet of said attritioning element to travel a substantially equal distance in return thereof to the inlet of the attritioning element, an inlet and outlet for the machine communicating with said passageway, an impeller journaled at the intake end of the machine for imposing a pressure greater than atmospheric upon the material in the machine.
6. In a machine of the character described, an attritioning element comprising a shell and a rotor, said attritioning element having a peripherally disposed inlet and outlet, a peripherally disposed passageway encompassing said attritioning element and connecting the said inlet and outlet thereof, the cross section of said passageway and the arrangement thereof relatively to said inlet and outlet being adapted to cause all particles of material passing from the outlet of said attritioning element to travel a substantially equal distance in return thereof to the inlet of the attritioning element, an inlet and outlet for the machine communicating with said passageway, an impeller journaled at the intake end of the machine, a screen element located between said impeller and the outlet of said machine adapted to retain in the machine that portion of the material not sufficiently treated and to permit the rest of the material to escape.

7. In a machine of the character described, an attritioning element comprising a conical shell and a rotor, said attritioning element having a peripherally disposed inlet and outlet, a peripherally disposed passageway encompassing said attritioning element and connecting the said inlet and outlet thereof, the cross section of said passageway and the arrangement thereof relatively to said inlet and outlet being adapted to cause all particles of material passing from the outlet of said attritioning element to travel a substantially equal distance in return thereof to the inlet of the attritioning element, an inlet and outlet for the machine communicating with said passageway, automatic means for feeding and discharging successive batches of material to and from the machine, such means adapted to hold the batch in the machine for a predetermined interval and to

then discharge the same by displacement due to the feeding of a further batch of material to the machine.

8. In a machine of the character described, an attritioning element comprising a conical shell and a rotor, said attritioning element having a peripherally disposed inlet and outlet, a peripherally disposed passageway encompassing said attritioning element and connecting the said inlet and outlet thereof, the rotor provided with a series of radial pivoted hammers of graduated lengths adapted to cooperate with the attritioning lining of the shell to attrition the material passing therethrough, the cross section of said passageway and the arrangement thereof relatively to said inlet and outlet being adapted to cause all particles of material passing from the outlet of said attritioning element to travel a substantially equal distance in return thereof to the inlet of the attritioning element, a screen element located between said impeller and the outlet of said machine adapted to retain in the machine that portion of the material not sufficiently treated and to permit the rest of the material to escape.

9. In a machine of the character described, an attritioning element comprising two relatively rotatable members, said attritioning element having a peripherally disposed inlet and outlet, a peripherally disposed passageway encompassing said attritioning element and connecting the said inlet and outlet thereof, the cross section of said passageway and the arrangement thereof relatively to said inlet and outlet being adapted to cause all particles of material passing from the outlet of said attritioning element to travel a substantially equal distance in return thereof to the inlet of the attritioning element, an inlet and outlet for the machine communicating with said passageway, an impeller journaled at the intake end of the machine for imposing a pressure greater than atmospheric upon the material in the machine.

10. In a machine of the character described, an attritioning element comprising two relatively rotatable members, said attritioning element having a peripherally disposed inlet and outlet, a peripherally disposed passageway encompassing said attritioning element and connecting the said inlet and outlet thereof, the cross section of said passageway and the arrangement thereof relatively to said inlet and outlet being adapted to cause all particles of material passing from the outlet of said attritioning element to travel a substantially equal distance in return thereof to the inlet of the attritioning element, an inlet and outlet for the machine communicating with said passageway, an impeller journaled at the intake end of the machine, a screen element located between said impeller and the outlet of said

machine adapted to retain in the machine that portion of the material not sufficiently treated and to permit the rest of the material to escape.

6 11. In a machine of the character described, an attritioning element comprising two relatively rotatable members, said attritioning element having a peripherally disposed inlet and outlet, a peripherally disposed 10 passageway encompassing said attritioning element and connecting the said inlet and outlet thereof, the cross section of said passageway and the arrangement thereof relatively to said inlet and outlet being 15 adapted to cause all particles of material passing from the outlet of said attritioning element to travel a substantially equal distance in return thereof to the inlet of the attritioning element, automatic means for 20 feeding and discharging successive batches of material to and from the machine, such means adapted to hold the batch in the machine for a predetermined interval and to then discharge the same by displacement due 25 to the feeding of a further batch of material to the machine.

12. In a machine of the character described, an attritioning element comprising two relatively rotatable members, said attritioning 30 element having a peripherally disposed inlet and outlet, a peripherally disposed passageway encompassing said attritioning element and connecting the said inlet and outlet thereof, the cross section of said passageway and the arrangement thereof relatively to said inlet and outlet being adapted to cause all particles of material passing from the outlet of said attritioning element to travel a substantially equal distance in 35 return thereof to the inlet of the attritioning element, an inlet and outlet for the machine communicating with said passageway, a supply tank connected with the said inlet of the machine, a valve in the said outlet of the machine, means operatively connected with said valve adapted to be actuated by a predetermined high level of the material, in said tank to open said valve and to be actuated by a predetermined low level of the material to 45 close said valve.

13. In a machine of the character described, an attritioning element comprising a conical shell and rotor, the rotor provided with a series of radial pivoted hammers of graduated lengths adapted to cooperate with the attritioning lining of the conical shell to attrition the material passing therethrough, the rotor and shell being relatively and axially adjustable one to the other, whereby 55 the rotor and shell may be brought more closely together or spaced further apart to regulate the attritioning action of the said hammers on the material.

14. In a machine of the character described, 60 an attritioning element comprising two rela-

tively rotatable conical members, an inlet to the machine arranged concentric with the axis of rotation of the attritioning element and a feeding and recirculation passageway peripherally encompassing said attritioning element, connecting the inlet and outlet thereof and communicating with said inlet and the outlet of the machine, said passageway providing a confining stock feeding circuit adapted to restrain short-circuiting in the flow of stock thru it.

15. In a machine of the character described, an attritioning element comprising two relatively rotatable conical members, an inlet to the machine arranged concentric with the axis of rotation of the attritioning element, a feeding and recirculation passageway peripherally encompassing said attritioning element, connecting the inlet and outlet thereof, said passageway providing a confining stock feeding circuit adapted to restrain short-circuiting in the flow of stock thru it, the receiving end of said passageway communicating with the inlet of the machine and its opposite end with the outlet thereof.

16. In a machine of the character described, an attritioning element comprising two relatively rotatable conical members, an inlet to the machine arranged concentric with the axis of rotation of the attritioning element, a feeding and recirculation passageway peripherally encompassing said attritioning element, connecting the inlet and outlet thereof, said passageway providing a confining stock-feeding circuit adapted to restrain short-circuiting in the flow of stock thru it, the receiving end of said passageway communicating with the inlet of the machine and its opposite end with the outlet thereof, and an impeller mounted above the said attritioning element in the inlet of the machine.

17. In a machine of the character described, an attritioning element comprising two relatively rotatable conical members, the larger end located adjacent the inlet of the machine, said inlet arranged concentric with the axis of rotation of the attritioning element, a feeding and recirculation passageway peripherally encompassing said attritioning element, connecting the inlet and outlet thereof, said passageway having a restricted conduit-like cross sectional area providing a confining stock feeding circuit adapted to restrain short circuiting in the flow of the stock, thru it, the receiving end of said passageway communicating with the inlet of the machine and its opposite end with the outlet thereof.

18. In the art of attritioning pulp and the like, the improved method which consists, in subjecting the pulp to repeated circulating and attritioning cycles and introducing measured units of untreated material at intervals

into said cycle, whereby to displace from said cycle units of treated material with units of untreated material.

19. In the art of attritioning pulp and the like the improved method which consists, in subjecting the pulp to repeated circulating and attritioning cycles under pressure greater than atmospheric and introducing under induced pressure measured units of untreated material at intervals into said cycle whereby to displace from said cycle units of treated material with units of untreated material.

20. In the art of attritioning pulp and the like, the improved method which consists, in subjecting the pulp to repeated circulating and attritioning cycles under pressure greater than atmospheric and introducing under pressure measured units of untreated material at timed intervals into said cycle, whereby to displace from said cycle units of treated material with units of untreated material.
